UNITED STATES PATENT OFFICE.

FREDERICK M. BOWERS, OF CHESTER, PENNSYLVANIA.

WELDER'S HELMET.

Application filed April 2, 1925. Serial No. 20,059.

My invention relates to welders' helmets adapted for use in shielding the eyes from the blinding light rays of a welding arc.

As the welding progresses, it may be inspected with the naked eye if the helmet is swung back above the head to give the eyes a clear view of the work. In close and cramped places, it is inconvenient and often impossible to swing the entire helmet above the head. This compels the welder to move out of the cramped place to a position where he may swing the helmet above his head, and thus causes inconvenience and loss of time to the welder when it is desired to inspect the work.

In helmets provided with strip springs for clamping the head band to the head, the hair is liable to catch between the springs and band and cause discomfort to the wearer.

The objects of my invention are to provide a helmet which will sufficiently shield the eyes from the light rays of a welding arc; which may be swung to an open position in close and cramped places to give the eyes a clear view of the work; which will be yieldably held in open and closed position, and in which the head gear will be free of parts likely to be caught in the hair of the user.

These objects, and other advantageous ends which will be described hereinafter, I attain in the following manner, reference being had to the accompanying drawings in which—

Figure 1 is a side elevation of a helmet made in accordance with my invention,

Figure 2 an enlarged central section through the helmet shown in Figure 1,

Figure 3 a like view showing the parts in another position,

Figure 4 an enlarged section on line 4—4 of Figure 2,

Figure 5 an enlarged section on line 5—5 of Figure 4, and

Figure 6 an enlarged section on line 6—6 of Figure 3.

Referring to the drawings, 1 indicates the lower shielding section of a helmet adapted to shield the lower part of the head of the user, 2 an upper shielding section adapted to shield the upper part of the head of the user having a hood 3 riveted thereto, and 4 a pair of bolts pivoting the sides of the upper section to the sides of the lower section. Head gear 5 is pivoted on bolts 4. It in-

cludes a head strip 6, a reinforcing strip 7 and a top strip 8. These strips are secured to each other by rivets 9. The top strip has its ends looped at 10 and secured to itself at 11. The loops are pivoted on bolts 4 on the inner side of the lower helmet section 1.

A coiled spring 12 is interposed between the head of each pivot bolt 4 and a loop 10 for frictionally holding the loops of the head gear to the lower section. The tension of this spring may be varied by tightening a nut 13, on the threaded end of bolt 4, against the outer side of the lower helmet section. For preventing a binding engagement of the upper section 2 against the lower section 1, a spacer 14, slightly thicker than the sheet material from which the upper section is made, is interposed between the outer side of section 1 and a washer 15. This arrangement allows varying tension to be placed on spring 12 without binding the upper section to the lower section.

The head strip 6 is of U-section and has strip springs 16 secured between the legs of the U. The curved part of the U forms the lower edge of the strip, so that when the head gear is fitted on the head, the curved edge will slide smoothly on the hair and will prevent spring 16 from catching the hair.

To yieldably keep upper section 2 in open or closed position, a coiled spring 17 has one end connected directly to the upper section by a rivet at 18, and the other end connected indirectly to the lower section by a ring 19, pivoted at 20 to a plate 21 secured to lower section 1. The connections 18 and 20 of spring 17 are so disposed that a line 22 passing through the connections, will be at one side of pivot bolt 4, when section 2 is in closed position, as shown in Figure 2, and at the other side of the bolt, when section 2 is in open position as shown in Figure 3. This arrangement of spring 17 tends to pull section 2 upwardly when in open position and downwardly when in closed position. The upward movement of section 2 is limited by an inclined edge 23 on the section 1 abutting an edge 24 of hood 3. The downward movement of section 2 is limited by a ledge 25, integral with a shielding strip 26 secured to section 1, abutting an edge 27 of section 2. Strip 26 shields the eyes from the light rays that may pass between the meeting parts of sections 1 and 2. A metallic lens frame 28 is mounted on section 2 in such position that its edge 29 is flush

with edge 27 and thus reinforces the same against wear caused by striking ledge 25. Suitable lenses 30 are mounted in the frame and held by a spring strip 31 between a pair of ribbed lugs 32 on lens frame 28. A cross piece 33 of V-cross-section is pivotally secured to the sides of helmet section 1 at 34. This cross piece reinforces section 2 and abuts the chin of the user to hold the helmet 10 in proper position relatively to the head, as shown in Figure 3.

To apply the helmet, the head gear is slipped over the head so that head strip 6 slides on the hair until top strip 8 abuts the 15 top of the head as shown in dot-and-dash lines in Figure 3. Cross piece 33 is then adjusted on its pivots 34 to the proper position against the chin. To inspect the work with the naked eye, it is merely necessary 20 to swing the upper section 2 from the position shown in Figure 1 to the position shown in Figure 2. This gives the eyes a wide view of the work, in front and at the sides of the helmet. The upper section is 25 held in this open position by the action of coiled spring 17 tending to raise section 2 against the inclined edge 23 of lower section.

1. After inspection of the work, section 2 is lowered until its edge 27 abuts ledge 25. 30 Section 2 is held in this position by the action of coiled spring 17 tending to pull it downwardly against ledge 25. Coiled spring 17 thus yieldingly holds section 2 in open or closed position. Shielding strip 26 prevents 35 light rays from passing between ledge 25 and edge 27 and serves to support ledge 25.

By making a helmet in sections and connecting the sections as above set forth, a section of the helmet may be easily swung 40 upward to give the eyes a wide view of the work when the welder is in close and cramped places.

While I have described my invention as taking a particular form, it will be understood 45 that the various parts may be changed without departing from the spirit thereof, and hence I do not limit myself to the precise construction set forth, but consider that I am at liberty to make such changes and 50 alterations as fairly come within the scope of the appended claims.

Having thus described my invention, what I claim as new and desire to secure by Letters Patent is:—

55 1. A helmet including a lower shielding section; an upper shielding section having its sides pivoted to the sides of the lower section and adapted to swing from the lower section to open position above the head of the user; lenses carried by the upper section, and means connected with the sections for keeping the upper section in open or closed position.

60 2. A helmet including a lower shielding section; an upper shielding section having its

sides pivoted to the sides of the lower section and adapted to swing from the lower section to open position above the head of the user; lenses carried by the upper section, and means connected with the sections for 70 yieldably keeping the upper section in open or closed position.

3. A helmet including a lower shielding section; an upper shielding section having its sides pivoted to the sides of the lower section and adapted to swing from the lower section to open position above the head of the user; lenses carried by the upper section, and resilient means connected with the sections for 75 yieldably keeping the upper section in open or closed position.

4. A helmet including a lower shielding section; an upper shielding section having its sides pivoted to the sides of the lower section and adapted to swing from the lower section to open position above the head of the user; lenses carried by the upper section, and resilient means connected with the sections for 80 yieldably keeping the upper section in open or closed position.

5. A helmet including a lower shielding section; an upper shielding section having its sides pivoted to the sides of the lower section and adapted to swing from the lower section to open position above the head of the user; lenses carried by the upper section; a spring connected to the upper section at 85 one side of the pivot and to the lower section at one side of the pivot and to the lower section at the other side of the pivot for yieldably keeping the upper section in open or closed position.

6. A helmet including a lower section; an upper section pivoted thereto and adapted to swing from the lower section to open position; lenses carried by the upper section; a spring connected to the upper section at one side of the pivot, and a ring connected with the spring, embracing the pivot and connected to the lower section at the other side of the 105 pivot.

7. A helmet including a lower section; pivot bolts passing through the opposite sides of the lower section; springs on the bolt abutting their heads; head gear on the pivot bolts between the springs and the inner side of the section; spacers on the bolts at the outer side of the section; an upper section pivoted on the spacers, and means on the bolts for holding said upper section on the spacers, whereby tension may be placed on the spring without binding the upper section to the lower section.

8. A helmet including a lower section; pivot bolts passing through the opposite sides of the section; head gear mounted on the bolts at the inner side of the section; spacers on the bolts at the outer side of the section; an upper section pivoted on the spacers, and means for securing the upper 120 125 130

section on the spacers, whereby the head gear may be clamped to the lower section without binding the upper section thereto.

9. A helmet including a lower shielding section; an upper shielding section having its sides pivoted to the sides of the lower section and adapted to swing from the lower section to open position above the head of the user; a shielding plate extending above the upper edge of the lower section; a ledge secured to the shielding plate and adapted to be abutted by the lower edge of the upper section when in closed position; a lens frame secured to and having its lower edge flush with the lower edge of the upper section to reinforce the same; lenses mounted in the frame, and means for keeping the upper section in open or closed position.

10. A helmet including a lower shielding section; an upper shielding section having its sides pivoted to the sides of the lower section and adapted to swing from the lower

section to open position above the head of the user; a shielding plate extending above the upper edge of the lower section; a ledge secured to the shielding plate and adapted to be abutted by the lower edge of the upper section when in closed position; a lens frame secured to and having its lower edge flush with the lower edge of the upper section to reinforce the same; lenses mounted in the frame, and means for keeping the upper section in open or closed position.

11. In combination with a helmet, head-gear secured thereto including a head strip of U-cross section, the curved part of the U forming the lower edge of the strip, and a spring secured to the strip between its sides.

In testimony whereof I have signed my name to this specification.

FREDERICK M. BOWERS.
